CLAIM

The ornamental design for an strapless, backless brassiere, as shown and described.

DESCRIPTION

FIG. 1 perspective view of the present invention depicted on a model and adhered thereon by tape (the model and tape being formed in phantom lines and forming no part of the design);

FIG. 2 is a front view of the present invention;

FIG. 3 is a top view of the present invention;

FIG. 4 is a bottom view of the present invention;

FIG. 5 is a back view of the present invention;

FIG. 6 is a left end view of the present invention; and,

FIG. 7 is a right cross section view of the present invention. The broken lines shown on the surface of the claimed design throughout the views are understood to represent stitching.

1 Claim, 2 Drawing Sheets
